UNITED STATES PATENT OFFICE

148,465

DESIGN FOR A CHARM OR SIMILAR ARTICLE

David Gordon, Los Angeles, Calif.

Application May 28, 1946, Serial No. 130,161

Term of patent 3½ years

(Cl. D45—17)

To all whom it may concern:

Be it known that I, David Gordon, a citizen of the United States of America, residing in Los Angeles, county of Los Angeles, and State of California, have invented a new, original, and ornamental Design for a Charm or Similar Article, of which the following is a specification, reference being had to the accompanying drawing, forming part thereof.

Fig. 1 is a front perspective view of a charm or similar article showing my new design.

Fig. 2 is a rear perspective view thereof.

Fig. 3 is a front perspective view illustrating the mouth portion in open position.

I claim:

The ornamental design for a charm or similar article, substantially as shown.

DAVID GORDON.
